UNITED STATES PATENT OFFICE.

JOHANN TASTO, OF TREYNOR, IOWA.

TORPEDO.

941,111.

Specification of Letters Patent. Patented Nov. 23, 1909.

Application filed June 10, 1909. Serial No. 501,422.

To all whom it may concern:

Be it known that I, JOHANN TASTO, a subject of the Emperor of Germany, residing at Treynor, in the county of Pottawattamie and State of Iowa, have invented certain new and useful Improvements in Torpedoes, of which the following is a specification.

This invention pertains to the art of naval warfare, and relates particularly to what are known as automobile torpedoes.

The invention comprises certain specific details of construction hereinafter fully described and claimed, and illustrated in the accompanying drawings, in which—

15 Figure 1 is a diagrammatic representation of the invention in actual use; Fig. 2 is a vertical longitudinal section of the torpedo; Fig. 3 is a vertical transverse section on the line 3—3 of Fig. 2; Fig. 4 is a bottom plan 20 view of a portion of the steering mechanism, and Figs. 5 and 6 are detail perspectives of parts of the operating mechanism hereinafter described.

Throughout the following detail description and on the several figures of the drawings similar parts are referred to by like reference characters.

As indicated in Fig. 1 a torpedo 10 is presumed to be despatched from a war vessel 11, or possibly from a shore fortification, and the same is being directed toward an enemy's vessel indicated diagrammatically at 12. The torpedo 10 is designed to be operated just beneath the surface of the water, but is provided with light standards 13 and 14 which project above the surface of the water. The standard 13, adjacent to the front end of the torpedo is made higher than the other so that both of the lights 30 13 and 14 would always be visible from the despatching vessel, and the lights are preferably of different colors, such as red and green or red and white, whereby the officers despatching the torpedo may the more readily control its operations.

In devices of this character it is customary for the torpedo to be equipped with self propelling mechanism and for it also to be provided with steering devices, and for the propelling and steering devices to be controlled from the despatching vessel by means of a series of electric wires extending between the despatching vessel and the torpedo in the form of a cable 15 which pays out in 40 accordance with the travel of the torpedo.

The cable 15 may be buoyed up by a series of floats if found necessary.

The torpedo is provided with an explosive 17 in its forward end adapted to be exploded when the point or end 18 of the torpedo 60 strikes the obstacle or enemy. At any convenient place, preferably near its rear end is shown a motor 19 for the purpose of driving the propeller screw 20. The operation of the motor will be controlled through the 65 wire 21 in any convenient and well known manner, such devices, *per se* not constituting the present invention.

The casing 22 of the torpedo is substantially cylindrical in form and is provided 70 on its bottom with a keel 23, of lead or some other heavy material so as to maintain the device righted and at the proper elevation with respect to the surface of the water. At its rear end the frame work of the casing 75 is extended to form supports for the rudder and steering mechanism. The extension 24 is in the form of a hollow chamber above the screw propeller 20, which chamber 24 encloses the principal parts of the steering 80 mechanism in a water-tight position. The extension 25 extends rearwardly from the keel. The rudder 26 is connected to a vertical shaft 27, journaled in and through the casing 24 at its upper end and in a step bearing in the extension 25 at its lower end. Connected to the shaft 27 within the chamber 24 is a gear or segment 28 adapted to be 85 operated slowly by a series of pinions and gears 29, 30, 31, and 32, the member 32 being a worm wheel adapted to be rotated in either of two directions by means of a worm 33 mounted on a horizontal shaft 34 journaled in bearings 35 connected to the inner 90 wall of the torpedo casing 22. The shaft 34 is provided with a belt pulley 36 around 95 which operates a drive belt 37. The worm 33 serves not only as a means for driving the steering mechanism in either direction but also serves as a positive lock preventing lateral swinging of the rudder while the worm is stationary.

The torpedo is equipped preferably midway between the explosion chamber and the driving motor with independent motors 38 105 and 39. These motors may be operated from any suitable source of power, the motor 38 being controllable by wires 40 and the other motor by wires 41, all of said wires being included in the cable 15 above mentioned. 110

The purpose of the motors 38 and 39 is to control the operation of the steering mechanism, especially to drive the same in one direction or the other or when the motors are stopped the rudder will be held stationary. In order to accomplish the above result in the most satisfactory manner there is provided a shaft 42, preferably vertically positioned in bearings 43 and 44 secured in the top and bottom of the interior of the casing. The shaft 42 furthermore is journaled and braced for rotation in supports 45 and 46, mounted rigidly and stationarily transversely of the casing 22. The shaft 42 is provided near its upper end with a belt pulley 47 over which the belt 37 operates, and is also provided with toothed hubs 48 and 49, the teeth of said hubs extending in opposite directions. A pair of pulleys 50 and 51, slidably and loosely mounted upon the shaft 42 and each of said latter pulleys is provided with a set of teeth 52 and 53, co-operating respectively with the hubs 48 and 49. The pulleys 50 and 51 are connected by belts 54 and 55 whereby they are alternately operated in opposite directions from the motors 38 and 39, respectively. In order to effect co-operation between the pairs of hub teeth above mentioned, the pulleys are provided with sets of strong spring teeth 50^a and 51^a. These teeth extend below the lower surface of the pulleys and have spiral disposition with respect to the shaft 42, the teeth of one pulley extending in a direction opposite from those of the other pulley. The supports 45 and 46 carry stationary blocks 56 and 57 provided with spiral holes or sockets 56' and 57', complementary to the several sets of teeth 50^a and 51^a. The blocks may also be provided adjacent to the margins of the sockets with upwardly projecting lugs 58 in order to insure proper operation of engagement of the teeth with the sockets if found necessary.

Assuming that the motor 38 is operated and the motor 39 is dead the belt 54 and pulley 50 will be in the direction indicated by the arrow *a*, and this operation of the pulley 50 will operate the steering mechanism in a certain direction for guidance of the torpedo accordingly. At this time the teeth 52 will be in engagement with the teeth of the hub 48, and such engagement will be maintained either by such engagement or by virtue of the spring teeth 50^a riding idly upon the upper surface of the block 56. The rotation of the shaft 42 and the hub 49 in such instance will cause the points of the spring teeth 51^a to enter the sockets 57' of the block 57 and by virtue of the form and disposition of said spring teeth 51^a the pulley 51 will be drawn downwardly disconnecting its teeth 53 from the hub 49. The motor 39 being dead will permit a slight reverse rotation in order to accomplish the above result.

The pulley 51 will be maintained therefore in engagement with the block 57 so long as the motor 38 is in operation. If it be desired to reverse the steering mechanism the motor 38 will be stopped and the motor 39 started. The belt 55 will then be operated in the direction indicated by the arrow *b* causing the pulley 51 to be withdrawn from the block 57 and into engagement with the hub 49, reversing the direction of the shaft 42. The effect of such reversal upon the pulley 50 will be the same as above described in connection with the pulley 51 while the motor 38 was in operation.

The device just described for controlling the steering mechanism is of peculiar advantage because of its simplicity and certainty of operation, matters of vast importance in devices of the nature of this invention. The lamps 13' and 14' are preferably lighted from batteries 13^a and 14^a, located at any convenient place within the casing 22 and having ordinary electrical connections therewith. The motors 38 and 39 are independently operated or controlled through their wires 40 and 41, respectively, extending along or within the cable 15 to the place or vessel from which the torpedo has been despatched. The motive circuit through either pair of wires is made or broken by means of a button or switch of a construction well understood in the art and which it is deemed unnecessary to illustrate.

Having thus described the invention, what is claimed as new is:

1. In a self-propelled torpedo, the combination with the casing, of propelling mechanism therefor including a motor and a screw, the motor being within the casing, and a portion of the casing being extended rearwardly forming a chamber over the screw, a rudder shaft extending into and journaled in said chamber, a rudder mounted on said shaft, a train of gears within said chamber to operate said rudder shaft, independently operated motors within the casing to operate said rudder through said train of gears in either of two directions, and electrical connections to said motors.

2. In a self-propelled torpedo, the combination of a casing having rearward extensions, a rudder journaled in said extensions, a pair of independently controllable motors within the casing, a shaft, gearing connecting the shaft with the rudder, a pair of loose pulleys mounted on said shaft, said pulleys being adapted to be operated from the respective motors in opposite directions, means whereby either of said pulleys may rotate said shaft when driven by its motor, and means whereby such operation of the shaft will render the opposite pulley inoperative.

3. In a self-propelled torpedo, the combination of a casing, a rudder connected to

the casing, a pair of independently controllable motors within the casing, a vertical power shaft journaled in the casing, connections between said shaft and the rudder, said 5 connections including a worm and worm wheel, a pair of stationary supports mounted in said casing, a pair of blocks having spirally arranged sockets, those of one block being directed oppositely from those in the 10 other block, a pair of pulleys loosely and slidably mounted on said shaft and having

teeth to coöperate with the respective stationary blocks, driving connections between the several motors and said loose pulleys, substantially as set forth.

15

In testimony whereof I affix my signature in presence of two witnesses.

JOHANN TASTO.
